Josiah Stubbs

UNITED STATES PATENT OFFICE.

JOSIAH STUBBS, OF DUBLIN, INDIANA.

CHURN.

Specification of Letters Patent No. 24,673, dated July 5, 1859.

To all whom it may concern:

Be it known that I, JOSIAH STUBBS, of Dublin, in the county of Wayne and State of Indiana, have invented a new and useful Improvement in Churns; and I do hereby declare that the following is a full and clear description thereof, reference being had to the accompanying drawings and to the letters of reference marked thereon and made 10 to form a part of this specification.

My invention relates to the construction, arrangement and operation of hinged dashers, within churns, by means of which great facilities are afforded in churning as herein- 15 after set forth and described.

In reference to the accompanying drawings, Figure 1 is a view of the exterior of the improved churn. Fig. 2, is a plan or top view of the churn, the cover being re- 20 moved in order to show the arrangement of the dashers. Fig. 3, is a vertical sectional elevation of the churn showing specially the manner of operating the dashers.

(A) represents the shell of the churn pro- 25 vided with stay pieces (a).

(b) is a central bar, the ends of which are made with slots, shown in Fig. 2, which are fitted to and made to slide upon the stay pieces (a). This bar (b) is adjustable ver- 30 tically by means of notches (a') of the stay pieces (a) and the set screw c.

Hinged to the bar (b) are two dashers (d, d) made with projecting flanges (e) and formed to fit loosely within the shell (A) 35 these dashers (d, d) are operated by means of rods (g, g) and crank (h) (k).

The operation of my invention may be described as follows: The fluid to be churned will be placed in the shell (A), and the bar (b) will be adjusted with reference thereto 40 in such manner that said bar may be barely covered with said fluid. Vibratory motion will then be imparted to the dashers (d, d) by means of the crank (h, k) and rods (g, g'). As the dashers are forced down- 45 ward the fluid will rush with great force around their outer edges against the shell (A) thereby securing a certain degree of concussion which greatly facilitates the process of churning. As the dashers are 50 drawn upwardly, a portion of the fluid will be retained upon them, by means of the flanges (e) and thrown violently together as the dashers reach their upper extremity of motion, thereby rupturing its vessels or 55 globules and securing great advantages in the rapidity of churning.

What I claim as my invention and desire to secure by Letters Patent is—

Operating the butterfly wings d and d, 60 with the single crank, k, confined to one side of the cylinder (g') being made to cross the body of the cylinder obliquely to effect this movement in the manner and for the purpose set forth. 65

In testimony of which invention I have hereunto set my hand.

JOSIAH STUBBS.
